MOUNTING PLATE FOR VACUUM PRODUCING APPARATUS

Richard C. Medley, Niles, Ill., assignor to Breuer Electric Mfg. Co., Chicago, Ill., a corporation of Illinois

Filed Jan. 25, 1963, Ser. No. 73,315

Term of patent 14 years

(Cl. D9—2)

FIGURE 1 is a top plan view of a mounting plate for vacuum producing apparatus showing my new design;

FIGURE 2 is an elevational view thereof from the rear;

FIGURE 3 is an elevational view of one side thereof;

FIGURE 4 is a bottom plan view thereof; and

FIG. 5 is a fragmentary cross-sectional view thereof, taken on the line 5—5 of FIG. 1.

I claim:

The ornamental design for a mounting plate for vacuum producing apparatus, substantially as shown.
